MOLDED CIGARETTE CASE

Otto Mayer, New York, N. Y.

Application May 26, 1943, Serial No. 488,518

6 Claims. (Cl. 206—41)

This invention relates to new and useful improvements in a molded cigarette case.

More specifically, the invention proposes the construction of a molded cigarette case characterized by a strip of flexible sheet material slightly wider than the package of cigarettes or the like article, and a molded sheet of flexible material having a front wall and side walls at the sides and bottom for holding the package of cigarettes, and also having outwardly directed flanged portions resting upon the face of the strip of flexible sheet material to be attached thereto for joining pieces of flexible material to form a unit thereof.

Still further it is proposed to extend a strip across the molded sheet of material and provide the strip of flexible sheet material with an extended top portion in the nature of a flap to be engaged beneath the center portion of the strap to close the open top of the cigarette case.

Still further it is proposed to provide a stiff U-shaped frame mounted in the bottom of the hollow of the molded sheet and which has its ends connected with the side walls of the molded sheet in a manner to shape the case and add rigidity thereto to prevent the package of cigarettes contained therein from being crushed while the case is in one's pocket.

A further object of the invention proposes a novel means for permitting the attachment of the ends of the U-shaped frame with the side walls of the case to be adjusted to compensate for stretching of the leather material from which the case is formed in a manner so that the case will always be extended to a position in which the cigarette package within the case will be protected at all times.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a molded cigarette case constructed in accordance with this invention.

Fig. 2 is a vertical sectional view taken on the line 2—2 of Fig. 1.

Fig. 3 is an inside perspective view of the molded flexible material, per se.

Fig. 4 is a front elevational view of a cigarette case constructed according to a modification of this invention.

Fig. 5 is an enlarged partial vertical sectional view taken on the line 5—5 of Fig. 4.

Fig. 6 is a vertical sectional view taken on the line 6—6 of Fig. 5.

5 Fig. 7 is a perspective view of the U-shaped frame, per se.

Fig. 8 is a view similar to Fig. 4 but illustrating a further modification of the invention.

10 Fig. 9 is an enlarged sectional view of a portion of Fig. 8.

Fig. 10 is a perspective view of one of the angle members used in the modification of the invention shown in Fig. 8.

15 The molded cigarette case, according to this invention, comprises a strip of flexible sheet material 10 which is slightly wider than the package of cigarettes or like article. A molded sheet 11 of flexible material is formed with a front wall 12 and side walls 13 at the sides and bottom 20 which extend rearwards to the face of the strip of flexible sheet material 10. The side walls 13 continue into outwardly extended flanges 14 which rest upon the front and side edge portions of the strip of flexible sheet material 10.

25 A strap 15 is extended across the face of the molded sheet 11 and has its ends adjacent the sides of the flanges 14. Lines of stitches 16 secure together the flange portions 14, the edge portions of the strip of flexible sheet material 10, and the ends of the strap 15 forming an integral unit of these parts. The strip of flexible sheet material has an extended top portion 17 in the nature of a flap which is adapted to be bent across the open top of the case and be engaged beneath the strap 15, as shown in Fig. 1, for closing the open top of the case.

It is proposed that the molded sheet 11 be shaped in a press by the application of pressure and heat. Details of the press for forming this molded sheet are not shown on the drawing as they form no part of the invention, and it is believed sufficient to merely include the above statement to explain the manner in which the molded sheet is formed.

45 In the modification of the invention shown in Figs. 4—7 the construction of the molded cigarette case is similar to that previously described, except for the application of a stiff U-shaped frame 18 of metal which is mounted in the bottom of the hollow of the molded sheet 12.

Means is provided for releasably connecting the top of the arms of the U-shaped frame with the adjacent side walls 13 of the molded sheet 11. This means comprises small outwardly extended 50 projections 19 formed on the ends of the U-

shaped frame 18 and which are releasably engageable with complementary openings 20 formed in the side walls 13 beneath the strap 15. The U-shaped frame 18 is applied to the interior of the cigarette case for the purpose of shaping the same and to give the side walls thereof stiffness to prevent the package of cigarettes engaged therein from being crushed while in one's pocket. In other respects, this form of the invention is similar to that previously shown and like reference numerals identify like parts in each of the several views.

In the modification of the invention shown in Figs. 8-10 the construction of the cigarette case is similar to that shown in Figs. 4-7, except for the provision of means whereby the attachment of the ends of the U-shaped frame 18' with the sides of the cigarette case may be adjusted to compensate for stretching of the material from which the cigarette case is made.

In this form of the invention small angle members 21 are attached in position between the adjacent faces of the flange 14 and the strip of flexible sheet material 19. These angle members 21 at their ends are provided with a plurality of openings 22 through which the stitches 16 are adapted to pass for securely locking the angle members in position. The other arms of the angle members 21 extend along the inside face of the side walls 13 and are provided with superimposed openings 20' with which the projections 19 of the U-shaped frame may be selectively engaged to adjust the position of the frame 18 with relation to the interior case. In other respects this form of the invention is similar to that previously shown and like reference numerals identify like parts in each of the several views.

It is to be understood that this arrangement may be used in connection with leather, imitation leather and with any suitable pliable material, such as double coated textile material.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said side walls and resting upon the bottom and side edge portions of said strip of flexible sheet material, a strap extended across said molded sheet, a line of stitches securing together said flange portions and the adjacent edge portions of said strip of flexible sheet material and the ends of said strap, and the top portion of said strip of flexible sheet material being in the nature of a flap engaging beneath said strap.

2. In a molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said

side walls and resting upon the bottom and side edge portions of said strip of flexible sheet material, a strap extended across said molded sheet, a line of stitches securing together said flange portions and the adjacent edge portions of said strip of flexible sheet material and the ends of said strap, and the top portion of said strip of flexible sheet material being in the nature of a flap engaging beneath said strap, said top portion being adapted to be bent over the open top of said case before being engaged beneath said strap.

3. In a molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said side walls and resting upon the bottom and side edge portions of said strip of flexible sheet material, a strap extended across said molded sheet, a line of stitches securing together said flange portions and the adjacent edge portions of said strip of flexible sheet material and the ends of said strap, and the top portion of said strip of flexible sheet material being in the nature of a flap engaging beneath said strap, and a stiff U-shaped frame mounted in the bottom of the hollow of said molded sheet, and means for releasably connecting the tops of the arms of said U-shaped frame with the adjacent side walls of said molded sheet.

4. In the molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said side walls and resting upon the bottom and side edge portions of said strip of flexible sheet material, a strap extended across said molded sheet, a line of stitches securing together said flange portions and the adjacent edge portions of said strip of flexible sheet material and the ends of said strap, and the top portion of said strip of flexible sheet material being in the nature of a flap engaging beneath said strap, and a stiff U-shaped frame mounted in the bottom of the hollow of said molded sheet, and means for releasably connecting the tops of the arms of said U-shaped frame with the adjacent side walls of said molded sheet.

said means comprising projections formed on the ends of said U-shaped frame and engageable with complementary openings formed in the side walls of said molded sheet beneath said strap.

5. In a molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said side walls and resting upon the bottom and side edge portions of said strip of flexible sheet material, a strap extended across said molded sheet, a line of stitches securing together said flange portions and the adjacent edge portions of said strip of flexible sheet material and the ends of said strap, and the top portion of said strip of flexible sheet material being in the nature of a flap engaging beneath said strap, and a stiff U-shaped frame mounted in the bottom of the hollow of said molded sheet, and means for releasably connect-

ing the tops of the arms of said U-shaped frame with the adjacent side walls of said molded sheet, said means comprising angle members having one of their arms disposed between the adjacent faces of said flexible sheet and said flange portions, and the other of their arms extended along the faces of said side walls, projections formed on the ends of said U-shaped frame and selectively engageable with complementary openings formed in the arms of said angle members which extend along said side walls.

6. In a molded cigarette case, a strip of flexible sheet material slightly wider than a package of cigarettes or the like article, a molded sheet of flexible material having a front wall and side walls at the sides and bottom for holding said package of cigarettes and also having outwardly directed flange portions continuing from said side walls and resting upon the bottom and side edge portions of said strip of flexible sheet material, a strap extended across said molded sheet, a line of stitches securing together said flange portions and the adjacent edge portions of said strip of

flexible sheet material and the ends of said strap, and the top portion of said strip of flexible sheet material being in the nature of a flap engaging beneath said strap, and a stiff U-shaped frame mounted in the bottom of the hollow of said molded sheet, and means for releasably connecting the tops of the arms of said U-shaped frame with the adjacent side walls of said molded sheet, said means comprising angle members having one of their arms disposed between the adjacent faces of said flexible sheet and said flange portions, and the other of their arms extended along the faces of said side walls, projections formed on the ends of said U-shaped frame and selectively engageable with complementary openings formed in the arms of said angle members which extend along said side walls, said arms of said angle members which extend between the faces of said flanges and strip of flexible sheet material being formed with openings through which said stitches may be engaged for locking said angle members in position.

OTTO MAYER.
